CLOTHES DRIER

Robert E. Little, % Arvin Industries, Inc., Columbus, Ind.

Filed Sept. 29, 1964, Ser. No. 81,930

Term of patent 14 years

(Cl. D49—1)

FIG. 1.

FIG. 2.

FIG. 3.

Des. 201,633

PAGE 2

Fig. 4.

Fig. 5.

FIG. 6.

FIG. 1 is a perspective view of a clothes drier, showing my new design, and showing the same in its storage and carrying position;

FIG. 2 is a rear elevation thereof;

FIG. 3 is a bottom plan view thereof;

FIG. 4 is a perspective view of the clothes drier shown in FIGS. 1 and 3, but showing the same in operative position;

FIG. 5 is an end elevation of the clothes drier shown in FIGS. 1-4, but showing the same in operative position and showing the end opposite the end shown in FIGS. 1 and 3; and

FIG. 6 is a rear elevation of the clothes drier in its operative position.

The dominant features of my design are shown in full lines.

I claim:

The ornamental design for a clothes drier, as shown and described.
